CLAIM

The ornamental design for a nailer housing head, as shown and described.

DESCRIPTION

FIG. 1 is a top, front, and right side perspective view of a first embodiment of the nailer housing head;

FIG. 1A is a partial section view taken through a portion of FIG. 1;

FIG. 2 is a front elevation view thereof;

FIG. 3 is a a rear elevation view thereof;

FIG. 4 is a right side view thereof;

FIG. 5 is a left side view thereof;

FIG. 6 is a top plan view thereof, and

FIG. 7 is a bottom plan view thereof.

FIG. 8 is a top, front, and right side perspective view of a second embodiment of the nailer housing head;

FIG. 9 is a front elevation view thereof;

FIG. 10 is a rear elevation view thereof;

FIG. 11 is a right side view thereof;

FIG. 12 is a left side view thereof;

FIG. 13 is a top plan view thereof; and,

FIG. 14 is a bottom plan view thereof.

The broken lines shown in the drawings illustrate portions of the nailer housing head that forms no part of claimed design.
